(57) **CLAIM**

The ornamental design for a breacher bag, as shown and described.

DESCRIPTION

FIG. 1 is a top, right front perspective view of my new design for a breacher bag, shown in use;

FIG. 2 is a top, right and front perspective view thereof;

FIG. 3 is a bottom plan view thereof;

FIG. 4 is a top plan view thereof;

FIG. 5 is a left side view thereof;

FIG. 6 is a right side view thereof;

FIG. 7 is a front view thereof; and

FIG. 8 is a rear view thereof;

FIG. 9 is an upper, right perspective view showing the design in a different configuration;

FIG. 10 is top plan view thereof;

FIG. 11 is a bottom plan view thereof;

FIG. 12 is a right side view thereof;

FIG. 13 is a left side view thereof;

FIG. 14 is a front view thereof; and,

FIG. 15 is a rear view thereof.

The broken lines depicting environmental structure are for illustrative purposes only and form no part of the claimed design. The break lines indicate that no particular length is being claimed.
